RAIL BRACE

James H. Asselin, Winnetka, Ill.

Application May 16, 1945, Serial No. 593,980

7 Claims. (Cl. 238—292)

1

This invention relates to rail braces for railway track. This application is a continuation-in-part of my copending application Serial No. 545,419, filed July 18, 1944. (Now Patent No. 2,419,701.)

As a train approaches a section of track, it sets up in that track a vertical up-and-down "wave" or "floating" motion of the rail. Heretofore, rail braces have not, if at all, dealt satisfactorily with these motions. In known adjustable rail braces the objective has been to have the assembly very rigid, with the result that these motions were transmitted through the rail brace and tie plate to the tie or to the tie and ballast, with the result that excessive wear and pumping of ties and ballast occurred. Prior designs, based on rigidity of track, were unsound since rigidity could not be permanently maintained.

Since rail wave motion is inherent in train movement over track, the present invention is based on the importance and necessity of flexibility in track and aims to allow and control wave action instead of trying to eliminate it completely.

In accordance with the present invention such wave motion in a limited degree is permitted, but is controlled above the tie plates, and only a minor portion is permitted to transcend through the tie plates into the ties or through the ties to the ballast. By so controlling and limiting this motion, the wear will be between the rail and tie plate, or between steel upon steel. Thus wear on ties and loosening of ballast is greatly reduced.

As will later be more apparent, the invention incorporates a hinge action fastening means, which provides the flexibility necessary to coincide with the "wave" or "floating" action of the rail.

Moreover, a brace stop is included that extends downwardly over the tie plate and holds the brace member continually in place. This brace stop assures continuous contact of the brace against the rail, and prevents the brace member from moving longitudinally with the rail when the wedge is driven into place.

Moreover, many adjustable rail braces are provided with bolts and nuts. The latter must be tightened from time to time inasmuch as they loosen with vibration. Some types also employ bolts which are inserted from the bottom of the base plate and are thus complicated and costly to install. In those types employing a wedge tightened by a bolt there is a real danger that turning the bolt too tightly will tilt the rail inwardly.

Still further, adjustable rail braces now known and which use nuts and bolts or ratchet toothed wedges or the like, are highly susceptible to wear, rust and corrosion due to weather conditions and salt brine. Many of them moreover are complicated by having too many parts, thus mate-

rially increasing the original cost, the cost of installation and the cost of maintaining proper adjustment.

These difficulties and disadvantages have been overcome by the present invention and it is a primary object of the invention to accomplish these aims.

A further object of the invention resides in providing a rail brace which may be used on switch rails, in turnouts, spring frogs, guard rails, curved rail in track, and on tangent track. Other uses will suggest themselves to those skilled in the art.

Records show that a large percentage of railroad accidents are the result of too wide track gauge. The gauge of track is frequently maintained by gauge rods which are connected to the base of one rail and with the base of the opposite rail. They are insulated when in a signal section area. Gauge rods have several defects. The insulation fouls, especially in wet weather, thus short-circuiting the signal system, but a more important defect is that the gauge of the bases only of the rails is maintained without assuring the gauge of the tops of the rails. The rail tops tip outwardly, thus throwing the rails out of gauge. Where, as in curves, frogs, guard rails and switch rails, the track is subjected to abnormal thrusts, the gauge of the rails thus frequently becomes too wide. In curves it has been found that the outer end of the base plate actually cuts into the tie one-half (1/2) inch by side thrust of the rail top, thus widening the gauge one (1) inch. The present invention applied at these sections of track will avoid these disadvantages of gauge rods and will prevent too wide gauge.

In its preferred form the contacting surfaces of the brace member and of the wedge are curved in profile forming a type of cylinder and socket joint which makes possible a hinging movement of the brace member and permits a limited amount of wave motion of the rail to occur. The cylinder and socket joint provides the greatest possible wearing area between brace member and wedge, thus making the necessity of adjustment less frequent. Moreover, such a cylinder and socket structure provides the greatest possible amount of bearing surface to best withstand stresses and strains in the device. It is an important object of the invention to provide such an arrangement.

The invention also has for an object the provision in one of its forms of a brace member which engages the rail only beneath the head and for a short distance down the web, said brace member being disposed in operation on a 45° line to provide a true bearing pressure against the web above the weakest section of the rail where the greatest bending stresses are present in the rail on curved track. The brace member in this form is urged toward the rail by a wedge.

The constant brace pressure against the upper part of the rail web, maintains canted rails in alignment with the bevel tread wheels. This provides true bearing on the rail head for greater wear.

Another object of the invention resides in the provision of a rail brace having an extra long canted base tie plate. This distributes the bearing loads more uniformly over the tie contact area and prevents cutting into the ties, thus assuring greater accuracy and providing for longer life.

These and other objects and advantages of the invention will become more apparent from the following specification and claims when read on the accompanying drawings in which;

Fig. 1 is an end elevation of a rail brace constructed in accordance with one form of the invention, the rail being shown in section;

Fig. 2 is a top plan view of the same;

Fig. 3 is a section taken on the line 3-3 of Fig. 2.

Fig. 4 is a front elevation of the same;

Fig. 5 is a side elevation of the brace member and wedge (shown separated);

Fig. 6 is a partial detail showing the use of insulation between the brace member and the rail;

Fig. 7 is an end elevation of a rail brace in accordance with another form of the invention;

Fig. 8 is a plan view of the same;

Fig. 9 is a fragmentary sectional view of a modified wedge for use with the invention.

Referring now more particularly to Figs. 1 to 5, inclusive, the numeral 10 indicates a railroad tie on which is disposed a rectangular metal base plate 11. In the form shown the upper surface of the base plate 11 is provided with a transverse groove or depression 12, the bottom surface of which slopes downwardly (from left to right in Fig. 1). The depression 12 results in the shoulder 13 which acts as transverse rail abutment.

The rail 14 is disposed with one (inner) edge of the base in engagement with the shoulder 13 and the other edge in engagement with a transverse rod 31 which is welded or otherwise secured to the upper surface of the base plate 11. The rail 14 is secured to the tie 10 by means of spikes 15 which are driven into the tie through openings 16 in the base plate 11 until the heads of the spikes engage the base flanges of the rail. The base plate 11 is also provided with openings 17 through which additional spikes or screws may be driven into the tie to secure the base plate to the tie.

The base plate 11 near its outer end is provided with a rectangular block 18 disposed transversely thereof. The block 18 may be integrally formed with the base plate, or may, as shown, be welded thereto. The inner surface of the block 18 and the rail engaging surface of the shoulder 13 are parallel. For purposes of the invention the inner surface of the block 18 is cut with a groove 19 which preferably is frusto-conical in section. Perhaps more properly speaking, the groove in section is in the shape of a truncated triangle.

The brace member proper is indicated by the reference numeral 20. This is an irregularly shaped member adapted to be disposed at substantially 45° with respect to the base plate 11. The brace member 20 has a rail engaging portion which, in use, engages the under surface of the rail head of the rail 14 and the uppermost portion of the rail web.

The base of the brace member 20 is semi-

cylindrical in shape, with the axis of the cylinder disposed at an angle with respect to the inner surface of the block 18.

For strengthening purposes the brace member 20 is provided with a centrally located strengthening rib 21.

Extending from one side end of the brace member is a lug 22 having a downward projecting portion which is adapted to engage the side edge of the base plate 11 to prevent forward movement of the brace member longitudinally of the rail as will be described.

The rail brace structure is completed by a wedge member 23, one side edge of which is provided with a tongue 24 of frusto-conical section or of a section which is in the shape of a truncated triangle and slightly smaller in area than the frusto-conical groove 19 in the block 18. The other side edge of the wedge member 23 is disposed at an angle to the block engaging surface which angle is parallel to the axis of the semi-cylindrical surface on the brace member 20. In section, the contour of the brace engaging surface of the wedge member 23 is concave and complementary to that of the semi-cylindrical portion of the brace member.

The wedge member 23 is adapted to be disposed in the angular position shown in Fig. 1 and is adapted to be driven in place longitudinally of the rail in such manner that the tongue 24 is disposed in the groove 19 while the concave sectioned surface of the wedge member engages the semi-cylindrical surface of the brace member 20.

Obviously, as the wedge member 23 is driven in place the brace member is forced against the rail 14 which it engages under the rail head and at the upper portion of the rail web. Movement of the brace member 20 longitudinally of the rail is prevented by the lug 22.

When the wedge member has been driven securely in place, it may be locked in position by means of a cotter pin 25 or the like which is passed through that hole of the series of holes 26 (Fig. 2) in the tongue 24 which is just clear of the end edge of the block 18. The use of this type of locking means is quite optional, for the wedge, when driven into place, is quite equivalent to the task of maintaining the rail brace in position with respect to the rail without requiring any auxiliary locking means.

In the early part of this specification reference was made to certain movements of the track section as a train approaches and passes. It was there stated that there is a vertical up and down "wave" or "floating" movement of the rail, which in a limited degree has been found to be necessary. Heretofore in rail braces the object has been to have the assembly so rigid that these motions are transmitted through the rail brace and base plate to the ties and ballast.

In accordance with the present invention, by reason of the slight clearance of the tongue 24 in the groove 19, a limited hinging movement of the wedge is permitted.

Moreover, it will be noted that the concave surface of the wedge member 23 and the semi-cylindrical surface of the brace member 20 comprise a form of cylinder and socket connection between the brace member 20 and the wedge member 23 when the wedge member is in final operative position. This cylinder and socket connection allows the brace member to describe a limited hinging or pivoting movement as the up and down "wave" or "floating" motion of the rail occurs, while at the same time the device

maintains the gauge of the rail head accurately. This cylinder and socket connection provides the greatest amount of bearing surface between the brace member and the wedge member and thus is designed to withstand best the stresses and strains in the rail brace.

The greater the area of contact between the brace member and the wedge member, the less frequently will the brace member require adjustment. It will be noted that this type of connection also provides the greatest possible wearing area between the brace member and the wedge member and this should reduce adjustments to a great extent.

It will be noted that, in accordance with the invention, the brace member is disposed substantially at a 45° angle to provide a true bearing pressure against the rail at the weakest section of the rail where the greatest bending stresses are present on curved track.

Attention is directed to the fact that the rail brace described is comprised of but three elements, the base plate 11 with its integral block 18, the brace member 20, and the wedge member 23. Thus the present invention not only provides a more satisfactory rail brace but does so with a minimum number of pieces which may be assembled without special tools, bolts, or the like. The rail brace described is particularly advantageous where used in connection with curved track.

Current day practice of rail inspection for defects and flaws is carried out with an inspection car provided with testing equipment operating on the magnetic field principle. It is manifest that the presence of an uninsulated rail brace, as on curves and the like, would increase the magnetic field and thus prevent accurate inspection with such equipment. This disadvantage is avoided in accordance with the present invention. In Fig. 6 it is illustrated that the rail engaging portion of the brace member 20 may be separated from the rail by an insulating member 27 which may be of any suitable material having good electrical insulating properties. Such insulating member 27 prevents the rail brace from increasing the magnetic field during the testing of the rail. It will be noted that the insulating member 27 also tends to reduce wear of the rail as well as of the brace member at the contact surfaces.

In accordance with another feature of the invention, the brace member may be constructed of a non-magnetic metal such as a manganese steel alloy or the like. In such event the magnetic field is not increased during testing even where no insulation material such as 27 is employed. Consequently, when use is made of a non-magnetic material for the brace member, the use of special insulating material 27 is optional.

In Figs. 7 and 8 an embodiment of the invention is disclosed which apart from the shape of the brace member is very similar to the form of invention disclosed in Figs. 1 to 5, inclusive. In describing the embodiment of Figs. 7 and 8 like reference numerals will be used to designate those elements which have been described in the first embodiment.

As will be immediately apparent from the drawings the principal differences reside in the fact that the brace member 28 curves from its wedge engaging portion inwardly toward the rail and then upwardly. The brace member 28 has two side walls 29 and 30 the upper edges of which engage the under surface of the head of

the rail 14 while the lower edges have portions which engage the upper surface of the base of the rail. The brace member 28 does not engage the web of the rail.

5 It will be clear that when the wedge member 23 is driven horizontally in place, in the same manner as described in the first embodiment, the brace member will be forced into engagement with the under surface of the rail head and the upper surface of the rail base.

10 It will be noted that a space is provided between the side walls 29 and 30 of the brace member 28 so that the brace member may be disposed in position over a rail spike without interference.

15 The type of rail brace illustrated in Fig. 7 is well suited for straight track but may, of course, also be employed on curved track and other types of track installations where rail braces are helpful. The brace member 28 may, as in the previous embodiment, be made of a non-magnetic material such as a manganese steel alloy or the like. Likewise, the use of a special insulating member (such as the member 27 in Fig. 6) is optional.

20 In all of the embodiments illustrated changes may be made without departing from the invention. For example, the tongue and groove connection between the block and the wedge member need not necessarily be as illustrated in Figs. 1 to 5 and 7 and 8. The tongue and groove may, for example, be of rectangular section as shown in Fig. 9. It is also apparent, that where a cylinder and socket connection is employed, as between the brace member and the wedge member, the concave and convex surfaces may be either on the wedge member or the brace member.

I claim:

40 1. A rail brace comprising, a base plate adapted to be disposed beneath a railroad rail, said base plate having a raised abutment for engaging one edge of the rail base, a block rigid with the base plate and spaced from the opposite edge of a rail when said rail is disposed in place on said base plate, said block having a surface facing toward said rail, a brace member for engaging the rail, said brace member being positioned between the rail and said block and having a surface facing towards said block, the facing surfaces of said block and brace member being contained in non-parallel planes, the surface of said block facing said rail having a longitudinal groove of rectangular section extending throughout its length, a wedge adapted to be driven horizontally between said block and said brace member, said wedge having side surfaces complementary to the adjacent surfaces of said block and said brace member, a rectangular sectioned tongue extending laterally from the side surface of the wedge adjacent said block for engagement within said groove when the wedge is driven into place, the cross sectional area of said groove being slightly larger than of said tongue, the facing surfaces of said wedge and said brace member being provided with complementary semi-circular profiles forming a cylinder and socket joint between said brace member and said wedge.

45 2. A rail brace comprising, a base plate adapted to be disposed beneath a railroad rail, said base plate having a raised abutment for engaging one end of the rail brace, a block rigid with the base plate and spaced from the opposite edge of a rail when said rail is disposed in place on said base plate, said block having a surface facing toward

said rail, a brace member for engaging the rail, said brace member being positioned between the rail and said block and having a surface facing towards said block, the facing surface of said block and brace member being contained in non-parallel planes, the surface of said block facing said rail having a longitudinal groove extending throughout its length, said groove in section having the shape of a truncated triangle, a wedge adapted to be driven horizontally between said block and said brace member, said wedge having side surfaces complementary to the adjacent surfaces of said block and said brace member, a tongue extending laterally from the side surface of the wedge adjacent said block for engagement within said groove when the wedge is driven into place, said tongue in section being similar to the section of said groove, the cross sectional area of said groove being slightly larger than that of said tongue, the facing surface of said wedge and said brace member being provided with complementary semi-circular profiles forming a cylinder and socket joint between said brace member and said wedge.

3. A three piece rail brace comprising a base plate the upper surface of which is provided with first and second abutments spaced from each other and adapted when in operative position to be disposed on opposite sides of a rail with the first abutment engaging one edge of the rail base and the other being spaced from the opposite edge of the rail, a brace member having a portion for engaging the rail and a portion disposed on said base plate, said latter portion having a side surface facing said second abutment, the facing surfaces of said brace member and said second abutment being contained in non-parallel vertical planes, a wedge having side surfaces complementary to the facing surfaces of said brace member and said second abutment, a tongue and groove connection between said wedge and said second abutment, said groove having a vertical distance greater than said tongue, the facing surfaces of said wedge and said brace member forming a cylinder and socket joint when the wedge is driven in place in a longitudinal direction between said brace member and said second abutment.

4. A rail brace as defined in claim 3, said base plate having spike openings for rail spikes and said brace member having spaces on its under side in alignment with said spike openings, whereby said brace member may be positioned snugly against a rail with the rail spikes located in said spaces.

5. A rail brace as defined in claim 3, said wedge comprising a single piece member, said brace member comprising a single piece member, and the engagement of said wedge between said second abutment and said brace member comprising the sole securing means for said wedge.

6. A rail brace comprising, a base plate adapted to be disposed beneath a railroad rail, said base plate having a raised abutment for engaging one edge of the rail brace, a block rigid with the base plate and spaced from the opposite edge of a rail when said rail is disposed in place on said base plate, said block having a surface facing toward said rail, a brace member having a portion for engaging the under surface of the rail head, said brace member being positioned between the rail and said block and having a surface facing to-

ward said block, the facing surfaces of said block and brace member being contained in non-parallel planes, the surface of said block facing said rail having a longitudinal groove extending throughout its length, said groove in section having the shape of a truncated triangle, a wedge adapted to be driven horizontally between said block and said brace member, said wedge having side surfaces complementary to the adjacent surfaces of said block and said brace member, a tongue extending laterally from the side surface of the wedge adjacent said block for engagement within said groove when the wedge is driven into place, said tongue in section being similar to the section of said groove, the cross sectional area of said groove being slightly larger than that of said tongue, the facing surfaces of said wedge and said brace member being provided with complementary semi-circular profiles forming a cylinder and socket joint between said brace member and said wedge.

7. A rail brace comprising, a base plate adapted to be disposed beneath a railroad rail, said base plate having a raised abutment for engaging one edge of the rail base, a block rigid with the base plate and spaced from the opposite edge of a rail when said rail is disposed in place on said base plate, said block having a surface facing towards said rail, a brace member having portions for engaging the under surface of the rail head and the upper surface of the rail base, said brace member being positioned between the rail and said block and having a surface facing toward said block, the facing surfaces of said block and brace member being contained in non-parallel planes, the surface of said block facing said rail having a longitudinal groove extending throughout its length, said groove in section having the shape of a truncated triangle, a wedge adapted to be driven horizontally between said block and said brace member, said wedge having side surfaces complementary to the adjacent surfaces of said block and said brace member, a tongue extending laterally from the side surface of the wedge adjacent said block for engagement within said groove when the wedge is driven into place, said tongue in section being similar to the section of said groove, the cross sectional area of said groove being slightly larger than that of said tongue, the facing surfaces of said wedge and said brace member being provided with complementary semi-circular profiles forming a cylinder and socket joint between said brace member and said wedge.
